(57) **CLAIM**

The ornamental design for a saddle pad as shown and described.

DESCRIPTION

FIG. 1 is a perspective view of a saddle pad.

FIG. 2 is a top plan view of the saddle pad of FIG. 1, the bottom plan view being a mirror image.

FIG. 3 is a front view of the saddle pad of FIG. 1.

FIG. 4 is a rear view of the saddle pad of FIG. 1.

FIG. 5 is a left side view of the saddle pad of FIG. 1.

FIG. 6 is a right side view of the saddle pad of FIG. 1; and, FIG. 7 is a perspective view of the saddle pad of FIG. 1 shown in an open position.

Portions of FIGS. 1 through 7 are shown in broken lines illustrating portions of the article that form no part of the claimed design. The stippling is used to indicate areas of contrasting color, which are a part of the claimed design.

1 Claim, 5 Drawing Sheets
